UNITED STATES PATENT OFFICE.

ROBERT FRANCIS FOSS, OF LACONIA, NEW HAMPSHIRE, ASSIGNOR OF ONE-HALF TO JACOB W. HADDOCK, OF SAME PLACE.

SAW-FILING DEVICE.

SPECIFICATION forming part of Letters Patent No. 599,327, dated February 22, 1898.

Application filed June 5, 1897. Serial No. 639,621. (No model.)

To all whom it may concern:

Be it known that I, ROBERT FRANCIS FOSS, a citizen of the United States, residing at Laconia, in the county of Belknap and State of New Hampshire, have invented a new and useful Improved Saw-Filing Device, of which the following is a specification.

My invention relates to an improved saw-filing device in which the saw-holding clamp 10 operates in conjunction with the adjustable reciprocating file-holding guide; and the objects of my improvements are, first, to provide a clamp which will hold the saw firmly in place at all points; second, which shall have 15 a traverse-way or slide-bar for the guide-carriage to move on; third, which shall be easily and quickly attachable to any bench, table, or other support on which it is to be used and as readily detached therefrom when desired 20 and which can be folded into a small compass for packing or transportation, the same to coöperate with the adjustable saw-filing guide, having lock-bolts to hold the several 25 adjustments firmly in place during the operation of filing the saw, said adjustments being arranged, as to the required angles, according to dials, on which are numbers and marks for such purpose, a device which can 30 be cheaply and durably made and easily operated and correctly set and reset. I attain these objects by the mechanism illustrated in the accompanying drawings, in which—

Figure 1 illustrates a plan or top view of my device; Fig. 2, a front view; Fig. 3, a side 35 view; Fig. 4, an end view; Fig. 5, a detail of handle-clamp; Fig. 6, a detail of bottom or base; Figs. 7 and 8, details of dials.

Similar letters and figures refer to similar parts throughout the several views.

40 A illustrates the base of the clamp part of my device, the lower part of which is made to fit onto the edge of a bench or any support to which it is to be secured for use, as shown in the drawings at a. It is secured to the 45 bench by means of the thumb-screw b. I sometimes use only an ordinary foot or base, which can be set on any part of the top of the bench, (see c,) in which case I secure said base to the bench by means of a bolt or thumb-screw d, which passes through the bench and 50 screws into the base, as shown at e. To the

upper part of said base A, I fit the clamp B by means of the swinging joint f and bolt g, the inner surface of said joint being roughened in any way, so as to make the friction 55 thereof more complete and prevent slipping when set together by the bolt g. Said bolt has a thumb-piece h thereon, which holds said joint in any position desired. On the upper part of B is one of the clamp-jaws, i. 60 The other clamp-jaw, j, is hinged to part l at m and is provided with an extension k. The jaws are firmly closed and locked in holding a saw by means of the thumb-screw n. There are projections on the side of the jaw i, to 65 which is attached the bar p by means of screws, on which bar the saw-guide slides freely.

By means of the joint f the parts A and B can be folded together, thereby making 70 the device more compact for packing or transportation.

The file-guide portion of my device is adjustable to any angle and at any degree required to fit any saw, (except a circular saw,) 75 and consists of the handle 1, with its index-collar 1', for determining the angle of the file in the handle to fit the desired pitch of the tooth of the saw. Into this handle is fitted the tang 2 of the file, the point of the file being 80 held in place by the arm 3, which is fitted on the sliding bar 4, to which it is secured in position by set-screw 5. Around said handle 1, just far enough back from the inner end of the handle to admit of a ferrule 6, fits the 85 other arm 7, which is made to fit loosely around said handle and is slotted, as shown in Fig. 5, and provided with a set or thumb screw 8, by which it is confined (by friction) at any angle or position desirable to fix and 90 hold the file from turning in practical use. This arm 7 is also fitted and secured to sliding rod 4 by a set-screw 9, as shown, Fig. 1. The rod 4 is made of such length as will accommodate any length of file and slide or reciprocate through two guides 1011, which extend from and on a part of the dial-plate 12. This dial-plate is marked and numbered in each direction alike from "0" and is adjustable from the mark on plate 13, by which the 95 adjustment of the file to a level of a cross-section of the saw or any departure there-

from is determined. When regulated, it is fastened by means of screw 14. Another dial 15, integral with dial 13 and provided with indicating-marks, is adjustably connected with sliding carriage 16, which moves on bar *p*, is made adjustable to plate 17 on carriage 16, and is to be permanently fixed at any desired point by set-screw 17', which is to determine the angle or shear of the tooth of the saw. It will be seen that when set to any point from one side of "0," if the dial is changed to the same number on the opposite side of "0," the file can be turned over and the saw turned end for end and the file will be set at the same angle at which it was first set and will give to the tooth of the saw the same angle as before making the change in the saw or guide. Said sliding carriage 16 is provided with slotted lugs 18 to fit freely on bar *p*, on which said carriage moves or reciprocates.

In operating my invention I first attach my

device to some bench or other support by means of the set or thumb screw *b* or *d*. I then secure the saw to be filed within the jaws of the clamp by means of the set-screw or thumb-screw *n*. I then arrange the angle for the file to run, both as to shear-angle and cross-angle, by the dials 12 and 15 and proceed to file the saw.

30

I claim—

In a saw-sharpening machine, the combination with the supporting-standard, of the clamping device hinged thereto and provided with the guide-bar *p*, carriage 16 to slide upon said bar, disk 13 pivoted to said slide, disk 12 having guides 10 and 11 and pivoted to said disk 13, and the file-carrier adapted to be slidably supported in the guides, substantially as shown and described.

ROBERT FRANCIS FOSS.
